UNITED STATES PATENT OFFICE

REINHARD LEISSNER, OF GARFIELD, NEW JERSEY

ARTISTIC CURTAIN

Application filed August 26, 1930. Serial No. 477,918.

This invention appertains to new and useful improvements in artistic curtains and shades.

The principal object of this invention is to provide a curtain or shade of opaque material, translucent designed, so that said designs will be clearly visible to persons in a room when there is a light outside.

Several important objects and advantages of the invention will be found in the following specification.

In the drawings:

Figure 1 represents an end elevational view of one form of the invention.

Figure 2 represents a sectional view, taken substantially on the line 2—2 of Figure 1.

Figure 3 represents an elevational view of a modification of the invention.

Figure 4 represents a sectional view, taken substantially on the line 4—4 of Figure 3.

Referring to Figure 1, it can be seen that numeral 5 represents a shade of opaque material wound on the roll 6 at one end and partly extended therefrom at its opposite end. The outer end portion of this shade is provided with an artistic arrangement of openings 6, of any shape and disposition, with a suitable fabric of sufficient translucency to permit the penetration of light therethrough. This fabric is preferably embroidered to the shade 5 at the edge portion of the opening.

The fabric pieces are cut to conform with the shape of the particular opening and do not transgress any portion of the shade between the openings.

The fabric inserts are denoted by numeral 7 and are also clearly shown in Figure 2.

Figure 3 is a modification of the invention and discloses the shade 5 provided with the artistic openings 6', in which suitable self-elastic translucent paper is inserted and secured at its edges to the edge portion of the shade at the said openings 6'. This translucent paper 7' may have suitable designs thereon.

While the foregoing specification sets forth the invention in definite terms, it is to be understood that numerous changes in the

shape, size, materials may be resorted to, without departing from the spirit and scope of the invention as claimed hereinafter.

What is claimed is:

As a new article of manufacture a window shade formed of opaque material and having ornamental openings in certain parts thereof, and a cover of translucent material for each opening, each cover being located on the rear face of the shade and embroidered through the shade with the embroidery surrounding the openings on the front face of the shade.

In testimony whereof I affix my signature.

REINHARD LEISSNER. 65
